DESIGN FOR A RADIANT HEATER

Jean O. Reinecke, Oak Park, Ill., assignor to
Sears, Roebuck and Co., Chicago, Ill., a corpo-
ration of New York

Application June 11, 1943, Serial No. 110,435

Term of patent 7 years

To all whom it may concern:

Be it known that I, Jean O. Reinecke, a citizen of the United States of America and resident of Oak Park, in the county of Cook and State of Illinois, have invented a new, original, and ornamental Design for a Radiant Heater, of which the following is a specification, reference being had to the accompanying drawing, forming a part thereof.

Fig. 1 is a front elevational view of a radiant heater embodying my new design.

Fig. 2 is a top plan view of the same.

Fig. 3 is a side elevational view of the said heater.

I claim:

The ornamental design for a radiant heater, substantially as shown.

JEAN O. REINECKE.
